HYDROCARBON COKING APPARATUS

Elmore S. Pettyjohn, Evanston, Ill., assignor to
 Institute of Gas Technology, Chicago, Ill., a
 corporation of Illinois

Application February 13, 1952, Serial No. 271,316

3 Claims. (Cl. 202—99)

1

This invention relates to method and apparatus for producing both coke and high heating value oil gas (700 to 1500 and preferably from 900 to 1100 or 1200 B. t. u./S. C. F.) from residual oils.

The term "residual petroleum oils" is herein employed by way of a distinction from distillate petroleum oils and refers to liquid petroleum oils or fractions of such oils characterized by a substantial Conradson carbon residue, say, 2 or more per cent by weight. In general these oils are characterized by a ratio of carbon to hydrogen of 6.5 or higher. Examples of "residual petroleum oils" are Nos. 5 and 6 fuel oils, Bunker "C" oil, heavy gas oil, heavy catalytic cracker residues, and cycle fuel oils.

When residual oils are cracked by being passed, in vapor form, through a hot tube to generate a high heating value fuel gas, other products than fuel gas are also formed, including carbon and tar (made up in part by light oils). Typically, a gallon of residual oil may yield, say, 4 pounds of gas, about 1 1/4 pounds of carbon, and about 2 1/2 pounds of tar. More than one-half of the tar may consist of pitch.

It is conventional to produce an oil gas of relatively high heating value by thermally cracking residual oils in vaporized form in an atmosphere of steam. On such thermal cracking of the indicated petroleum oils, carbon is deposited in the space where cracking is effected in an amount requiring frequent removal, as by burning, if cracking is to be continued in the same space. To handle such cracking, apparatus has heretofore been used comprising a generator in which cracking is effected and a super-heater in which the oil gas formed in the generator is cracked further. This apparatus is operated by alternately (1) spraying oil and introducing air at ambient temperature directly into the generator and there burning the oil to remove carbon deposited in the generator and superheater and to raise the generator and superheater to cracking temperatures and (2) spraying oil and introducing steam into the generator after the carbon has been removed and the generator and superheater have been raised to cracking temperatures. This is a cyclic, non-regenerative process.

By way of an improvement over the above described cyclic process including an oil cracking (or make) step and an oil and carbon burning (or heating or blasting) step, it has been proposed to provide apparatus including two left and right generator-superheater pairs and a con-

2

duit connecting the two generators, for use in a regenerative, cyclic process including two cracking or make steps or periods and two burning or blast steps or periods. More particularly, if a make period has just been terminated in the right generator-superheater, air is forced into and through the right generator-superheater for flow into the generator of the left pair where the air (then preheated by heat exchange and by combustion of carbon deposited during the make in the right generator-superheater) supports the combustion of the oil sprayed into the generator of the left pair, heating the generator and superheater of the left pair to cracking temperature. Oil is next cracked in the left generator-superheater in an atmosphere of steam. Next the right generator-superheater is heated by forcing air through the left generator-superheater into the generator of the right pair where the air (now preheated by heat exchange and by combustion of carbon deposited during the make in the left generator-superheater) supports the combustion of oil sprayed into the generator of the right pair. Finally, oil is cracked in the right generator-superheater in an atmosphere of steam.

With respect to fuel consumption for maintaining cracking temperature, the above-noted regenerative four step or period process carried out in two connected generator-superheater pairs is more economical than the above noted non-regenerative two step or period process carried out in a single generator-superheater pair. But the oil gases produced by the two processes are identical in composition and burning characteristics. As a matter of fact, the composition of the oil gas formed by these and other conventional cracking processes is fixed by the heating value of the gas produced, being independent of the nature of the oil being cracked and of the residence time. I have ascertained the relation between composition and heating value of oil gases produced by conventional cracking methods by subjecting various petroleum oils (including among others, diesel oil, 37.3° A. P. I., 0 weight per cent Conradson carbon residue, C/H=6.39; heavy gas oil, 22.2° A. P. I., 6 weight per cent Conradson carbon residue, C/H=7.05; and Bunker "C" fuel oil, 9.9° A. P. I., 11 weight per cent Conradson carbon residue, C/H=8.51) to thermal cracking at temperatures ranging from 1350° to 1700° F., residence times ranging from 1 to 5 seconds, and a partial pressure of oil gas ranging from 0.3 to 0.9 atmosphere. The value obtained under all these conditions from the vari-

ous oils show that the composition of the oil gas is a function of the heating value of the oil gas, as tabulated:

Gas Composition in Percent	Diluent Free Heating Value of Gas in B. t. u./S. C. F.					
	1,000	1,100	1,200	1,300	1,400	1,500
Paraffins	48	48	48	48	47	44
Ethylene	20	23	25	26	27	27
Higher Illuminants	4	6	8	10	13	18
Hydrogen	28	23	19	16	13	11

None of the above tabulated gases are completely interchangeable with natural gas, among other reasons because of their low contents of paraffins and their high contents of unsaturates which, as I have found, confer on these gases burning characteristics entirely different from those of natural gas. Reference is made to the copending application of myself and Henry R. Linden entitled "Fuel Gas Interchangeable with Natural Gas and Method of Making the Same" for a more complete discussion of the composition of gases interchangeable with natural gas. It is sufficient, for the purposes of the present application, to state that the above-tabulated gases can be blended with natural gas only to the extent of possibly 20% or 50%, if the resulting gas mixture is to be sent out for use in appliances adjusted for burning natural gas.

In the above noted conventional cracking methods, the carbon deposited in the course of the cracking is burned, to furnish a large part of the heat required for the cracking step. One reason for burning this carbon is the fact that the carbon is deposited in a form resembling lamp black, in which form the carbon is chiefly valuable only as a fuel. The same applies to the value of the pitch which forms the bulk of the tar obtained in the course of such thermal cracking. Further, to recover the heating values of the carbon and the pitch, it is practically almost necessary to burn these materials in the locality where they are produced. In other words, these materials, and particularly the carbon, could not conveniently be transported to other localities for burning in combustion devices such as steam boilers, for the purpose of recovering the heating values thereof.

Residual oils have also been subjected in liquid form to high temperature coking processes wherein the carbon and the pitch are in the form of coke. In some of the high temperature coking processes presently employed for the coking of heavy oils, a pool of oil is poured on the floor of a distillation chamber heated from below by the combustion of fuel in subjacent flues, the heat required for carbonization being conducted upwardly through said floor. After a first pool of oil has been coked, a second pool of oil is poured onto the coke formed from the first pool. The heat required for carbonization of the second pool is supplied to the pool through the floor of the carbonization chamber and through the first layer of coke formed from the first pool. This process is repeated until a layer of coke of suitable thickness has been formed on the floor of the chamber. With each successive layer of coke formed, the temperature inside the flues is progressively raised so that each layer of coke below the uppermost layer is subjected to increasingly higher temperatures for increasingly longer periods of time. As a result, the various layers of coke formed on the bottom of the cham-

ber are distinguished by widely variant characteristics, as are also the gaseous products obtained in the coking of the various pools of oil.

It has, therefore, been proposed to effect transmission of heat to a layer of oil or the like to be carbonized by downward radiation from a source of heat arranged at or near the top of a distillation chamber. However, with such an arrangement, the gases generated during destructive distillation rise and contact said source of heat, being cracked or carbonized with resultant deposition of carbon on the source of heat. In the destructive distillation of heavy oils or the like involving transmission of heat by radiation from above, the removal of carbon deposits from the source of radiant heat has therefore presented a difficult problem.

It is, therefore, an important object of the present invention to provide method and apparatus for thermally cracking residual petroleum oils in liquid form to produce both coke of uniform and consistent characteristics and a high heating value fuel gas more completely interchangeable or even absolutely interchangeable with natural gas, as compared with conventional high heating value oil gas.

Other and further objects and features of the present invention will become apparent from the following description and appended claims as illustrated by the accompanying drawings showing, diagrammatically and by way of examples, apparatus according to the present invention.

Figure 1 is a transverse cross sectional view, with parts shown in elevation, of a furnace according to the present invention; and

Figure 2 is a fragmentary longitudinal vertical cross sectional view taken along the line 2—2 of Figure 2.

My novel apparatus and method for thermally cracking residual oils in liquid form involves the transmission of heat to the liquid being cracked from above by radiation from hollow bodies supplied with air and fuel for internal combustion in said bodies. The latter are constructed of silicon carbide (Carborundum) and are able to resist temperatures as high as 2500° to 2600° F. or higher. Further, these bodies, according to my invention, are porous or permeable to gas, so that any carbon deposited on the outside of the bodies can be removed from time to time by forcing the gas outwardly through the porous or permeable bodies. If desired, outward flow of gas through the porous or permeable bodies can be maintained constantly, for preventing deposition on the porous bodies of carbon formed on cracking of the distillate. The actual temperature prevailing in the cracking step is about 1200° F. or higher and suitably between 1400° and 1800° F. At these temperatures, the products obtained are a rather large amount of high heating value oil gas, a relatively small amount of liquid distillate containing a relatively large proportion of aromatics, and a "dry" coke containing a relatively small amount of volatile matter, for instance, as little as 1.5%. In the cracking step, the oil gas and the vapor (of the distillate) are exposed to the heat in the furnace for a relatively short time, while the coke is exposed to the heat for a relatively long time, whereby the constituents of the volatile matter in the coke are cracked, to leave the above "dry" coke.

The oil gas generated in the above-described cracking step is characterized by a composition dependent upon the heating value of the oil gas

as tabulated hereinabove. But due to the short residence time of the gas within the above-mentioned apparatus for cracking the residual oils, the gas will ordinarily have a heating value in excess of 1200 B. t. u./S. C. F. This gas may be converted to a fuel gas absolutely interchangeable with natural gas by further cracking at 1350° to 1700° F., a pressure of from 1 to 5 atmospheres and a residence time of 1½ to 10 seconds, followed by autohydrogenation effected by contacting the gas with a conventional hydrogenation catalyst at a temperature of from 500° to 800° F. and a space velocity of from 100 to 1000 cubic feet per cubic foot of catalyst volume per hour.

Referring now to Figures 1 and 2, the reference numeral 10 designates generally a cracking furnace according to the present invention of generally rectangular vertical cross section formed with an internal coking chamber 11 defined by a coking floor 12, vertical side walls 13 and a roof 14, all preferably made of relatively non-porous refractory material of relatively low heat conductivity. The refractory material is insulated on the outside with suitable insulating material 16 to conserve heat and to maintain the coking chamber at substantially uniform temperature. The coking chamber is maintained at the desired temperature by means of heat radiating burner tubes 17 piercing the side walls. Oil to be coked is injected into the coking chamber through nozzles 20 extending through the side walls.

The tubes 17 are made of carborundum and are sufficiently porous or permeable to permit outward gas flow therethrough. If desired, these tubes may be made up in sections. A fluid fuel may be supplied to one end of the tube 17 (outside the left side of the furnace 10) through a valved conduit 21. On the right side of the furnace 10 the tube 17 discharges combustion gas into a downwardly and then inwardly extending tube 18 which in turn discharges into one of a plurality of transverse spaced channels 19 formed within the floor 12 of the furnace 10. These channels finally discharge the combustion gas into a stack 21 for venting to the atmosphere. Air under pressure is supplied from a conduit 22 through a plurality of valved pipes 23 each discharging air into one of a plurality of transverse spaced channels 24 formed within the floor 12 of the furnace 10 and extending between the channels 19. Each of the channels 24 supplies air (pre-heated by transfer of heat from combustion gas through the walls separating the channels 19 and 24) to one of the tubes 17.

In operation of the furnace 10 shown in Figures 1 and 2, a thin layer of granular or finely divided coke of the type obtained by the operation of said furnace is initially spread over the floor 12 of the chamber 11 to form a zone of cleavage between the coke subsequently produced in the furnace and the floor of the furnace, whereby the removal of the coke from the chamber at the end of the operating cycle is facilitated. The chamber 11 is next raised to the desired temperature (above 1200° F. and preferably from 1400° F. to 1800° F. in the coking of petroleum still residues) by combustion of the required amount of fuel and air in the combustion tubes 17. A predetermined amount of residual oil is next introduced into the chamber 11 through the nozzles 20 to form a relatively shallow pool on the floor 12 of the chamber where the oil remains until coked by the heat radiated from the combustion tubes 17. When

the first charge has been coked to form a layer of coke from ¼" to 1" thick, a second charge of substantially the same quantity as the first charge is admitted to the chamber 11 to form a second pool on top of the coke formed from the first charge. This operation is repeated with as many subsequent charges of material as is necessary to form a slab of coke of desired thickness, say, from 1" to 6". In this slab of coke, each layer is formed under substantially identical temperature conditions maintained for substantially the same length of time. The slab is, therefore, of uniform quality throughout.

As each pool of residue or tar or the like is being coked, the gases and vapors then generated rise from the pool towards the roof 14 of the chamber 11, come in contact with the surfaces of the tubes 17 heated by internal combustion and are cracked on these surfaces to form a layer of coke on the tube surfaces. This layer of coke, if permitted to remain on the tubes, would act as an insulator with the result that the temperature of the chamber would be lowered if the temperature is maintained constant within the combustion tubes, or the internal combustion temperatures would have to be raised to maintain a constant chamber temperature. In order to maintain a uniform coking temperature without any necessity for raising the internal combustion tube temperature, the coke is periodically cracked off from the combustion tubes 17 by periodically flowing a gas through the tubes 17 at sufficient pressure to cause outward gas flow through the tube walls. The rate of outward gas flow is controlled so that carbon deposited on the tubes will be peeled off. The coke peeled off from the tubes 17 falls on top of the layer being coked and is incorporated in the final slab of coke by the coking of a subsequent charge of oil or the like. The gas thus utilized for removing deposits of carbon may be combustion gas or may be a calorific gas or vapor that will not dilute the gas produced on destructive distillation so as to reduce the calorific value of the latter.

If desired, the pressure within the tubes 17 may at all times be maintained high enough to bring about constant outward gas flow through the tubes, for preventing the adherence to the tube of carbon formed on cracking of gases or vapors generated from the oil being cracked.

In the event that the tubes 17 are cleaned intermittently in the manner described, the frequency of such cleaning is determined by the rate of formation of gases and vapors contacting the tubes and on the coke forming characteristics of these gases and vapors. Such intermittent cleaning can be carried out automatically by any suitable means, for instance, thermostatic means controlled by the furnace temperature, by the temperature of the gases discharged from the tube 17 into the stack 21 or by any other suitable means, so that the desired chamber temperature is automatically maintained during the whole coking operation.

While the apparatus described by way of an illustrative example includes radiant tubes heated by internal firing, it should be understood that the tubes may be heated by passing hot gases therethrough formed by combustion elsewhere, as in a regenerative furnace.

The hot gases and vapors formed in the furnace 10 are discharged therefrom through any suitable conduit, such as that indicated at 26. These gases and vapors are maintained at a temperature of from 1350° F. to 1700° F. for from 1½

to 10 seconds in the next succeeding vapor phase cracking step. The pressure may range from 1 to 5 atmospheres. Since these gases and vapors are hot when discharged from the furnace 10, very little additional heat is consumed in the further cracking thereof.

The above noted gas phase cracking step is carried out principally to reduce the oil gas content of higher illuminants (particularly olefines other than ethylene), which may range, say, from 5% to 18%. These higher illuminants when thus cracked in vapor form yield a carbon deposit within whatever vessel is employed for the vapor phase cracking step. If, as may be done, the vapor phase cracking is carried out in a tube heated externally (if necessary) to maintain the above-noted cracking temperature, the carbon deposited in such a cracking tube may be returned to the furnace 10, for instance, to furnish the carbon layer initially deposited on the furnace floor 12 before liquid phase cracking is started in the furnace. In that event, the carbon from the cracking tube may be devolatilized completely or nearly completely (if not obtained in the cracking tube in "dry" form), and all the carbon formed from the oil being cracked is thus recovered in the form of coke. If the carbon deposit in the cracking tube is obtained in a form similar to lamp black, this carbon, when returned to the furnace 10 and wetted with the oil charged to the furnace, is incorporated with the coke formed in the furnace, being bonded together by the heavy carbonaceous constituents of the oil cracked in the furnace.

No particular showing in the drawings, nor any further discussion in this specification is believed required in connection with the above noted vapor phase cracking step as carried out in a heated tube, since such a procedure, in and by itself, is well within the skill of those versed in the art, in view of the preceding disclosure. It may be noted, however, that relatively small amounts of carbon are deposited from the gas being cracked so that this vapor phase cracking step ordinarily can be carried out continuously (without interruption for removal of deposited carbon) for as long a period of time as may be required between initiation of cracking in the furnace 10 and termination of cracking in the furnace 10 for removal of coke formed therein.

The oil gas obtained after said vapor phase cracking may be rendered absolutely interchangeable (if not so interchangeable) with natural gas by catalytic autohydrogenation. For this purpose, the gas is first passed through a condenser (to remove condensable oils) and thereafter over a hydrogenation catalyst. To secure such a gas absolutely interchangeable with natural gas, the catalyst temperature is maintained within the range of from 500° F. to 800° F. and the space velocity is maintained within the range of from 100 to 1000 cubic feet per cubic foot of catalyst volume per hour. The autohydrogenation can conveniently be carried out at atmospheric pressure, but somewhat better results are obtained at superatmospheric pressure. Any catalyst suitable for the hydrogenation of unsaturated hydrocarbons may be used, for instance, iron, nickel, cobalt, the oxides of these metals, platinum, palladium, vanadium and its oxide, and the oxides of chromium and molybdenum. By way of an example of such autohydrogenation, we have treated the above tabu-

lated make gas (after removal of condensable vapors) by passing this gas over a catalyst consisting of nickel oxide precipitated on a kieselguhr carrier and containing about 10% elemental nickel in oxide form. The temperature amounted to about 541° F. and the space velocity to about 151 cubic feet per cubic foot of catalyst volume per hour. The paraffin content of the gas was raised considerably, about 75% of the unsaturates being hydrogenated, and the gas was rendered absolutely interchangeable with natural gas.

Many details of construction and procedure may be varied without departing from the principles of this invention, and it is therefore, not my intention to limit the patent granted on this invention otherwise than necessitated by the scope of the appended claims.

I claim as my invention:

1. Apparatus for coking organic material comprising means defining a coking chamber adapted to have a layer of organic material spread over its floor, and a silicon carbide tube extending through the upper part of said chamber adapted to have fuel burned therein to generate heat to be radiated onto said layer of material for coking the same, said tube being permeable to gas so that carbonaceous deposits on said tube can be removed therefrom by establishment of outward gas flow through said tube walls.

2. Apparatus for coking organic material comprising means defining a coking chamber adapted to have a layer of organic material spread over its floor, a silicon carbide tube extending through the upper part of said chamber adapted to have fuel burned therein to generate heat to be radiated onto said layer of material for coking the same, said tube being permeable to gas so that carbonaceous deposits on said tube can be removed therefrom by establishment of outward gas flow through said tube walls, means for introducing a fuel and air into said tube to bring about combustion therein, and means in the floor of said apparatus for effecting heat exchange between said air and combustion gases formed in said tube.

3. Apparatus for coking organic material comprising means defining a coking chamber adapted to have a layer of organic material spread over its floor, a plurality of spaced silicon carbide tubes extending through the upper part of said chamber adapted to have fuel burned therein to generate heat to be radiated onto said layer of material for coking the same, said tubes having porous walls so that carbonaceous deposits on said tubes can be removed therefrom by establishment of outward gas flow through said tube walls, a plurality of spaced tubes receiving combustion gas from said carbide tubes and extending within the floor of said apparatus, and a plurality of air tubes extending within said flow between said combustion gas tubes to preheat air passing through said air tubes, said air tubes discharging into said carbide tubes.
